HIGH INTERRUPTING CAPACITY FUSE
 Frederick J. Kozacka, South Hampton, N.H., assignor to
 The Chase-Shawmut Company, Newburyport, Mass.
 Filed Feb. 18, 1963, Ser. No. 259,019
 9 Claims. (Cl. 200—120)

This invention is concerned with electric fuses, and more particularly with high interrupting capacity current-limiting fuses.

Achieving high interrupting capacity and a significant current-limiting action calls for the use of a pulverulent arc-quenching filler having a high heat absorbing capacity and capable of generating high arc-voltages. By far the most effective pulverulent arc-quenching filler complying with these requirements is quartz sand. Electric fuses which are filled with quartz sand must include casings which are heat resistant because quartz sand, being an excellent conductor of heat, tends to transfer large amounts of heat from the arcing zone inside the fuse to the casing thereof, imposing upon the latter a severe thermal duty. The requirements in regard to the heat resistance imposed upon the material of which the casing is made are particularly high when considering interruption of relatively small protracted overloads as, for instance, overloads of the order of 200% of the rated current of the fuse. In such an instance the quartz sand is heated to a relatively high temperature before the fuse link melts, and before the interrupting process is initiated. Intense pre-heating of the quartz sand results in a drastic reduction of its arc-quenching ability. Consequently pre-heating of the quartz sand tends to increase the arc energy, i.e. the total electric energy which is converted inside of the fuse into heat in the interval of time between arc inception and arc extinction. The severity of the thermal duty imposed upon a casing of an electric fuse is increased in proportion to arc energy.

While the thermal duty which is imposed upon the casing of a fuse varies with the amount of arc energy, all fuses comprising quartz sand as an arc-quenching filler, or arc-extinguishing medium, call for casings made of materials which are highly heat resistant, and heat-shock resistant. Such materials are, for instance, ceramic materials and/or synthetic-resin-glass-cloth laminates. Heat resistant materials are relatively expensive. As a result, the cost of manufacturing electric fuses having an arc-quenching filler of quartz sand and, therefore, calling for highly heat resistant casings, are likewise relatively high.

It is one object of this invention to provide high interrupting capacity current-limiting fuses which are filled with quartz sand, and which do not require casings of highly heat resistant and/or expensive materials.

The least expensive materials for making casings of electric fuses are cellulosic materials, e.g. paper or fiber. In the past these materials have been used extensively for making casings of fuses filled with arc-quenching fillers which are relatively poor thermal conductors as, for instance, gypsum, but these materials were found to be wholly inadequate for making high interrupting capacity current-limiting fuses including quartz sand as a filler.

It is, therefore, another object of this invention to provide high interrupting capacity current-limiting fuses having casings of cellulosic materials such as paper, or fiber, and being filled with quartz sand.

The thermal duty imposed upon the casing of an electric fuse while the latter is carrying load currents and during the interrupting process of the fuse depends, to some extent, upon the size of the casing of the fuse.

2

It is apparent that the aforementioned thermal duty might greatly be reduced by increasing the dimensions of the casings of electric fuses. That is, however, practically not feasible because the dimensions of electric fuses are 5 standardized. Most manufacturers of fuses follow these size standards, and some manufacturers of fuses make fuses having smaller dimensions than provided in the fuse standards. Fuses having larger dimensions than provided in the fuse standards are, however, unacceptable. Therefore it is unacceptable to increase the size of casings of fuses above and beyond standard dimensions in order to reduce the thermal duty which is imposed upon casings of electric fuses.

It is, therefore, still another object of this invention 15 to provide high interrupting capacity current-limiting fuses having casings of standard dimensions—or even smaller dimensions than standard dimensions—which casings are made of cellulosic materials such as paper, or fiber, and are filled with quartz sand.

20 Still another object of this invention is to provide novel and improved electric fuses which, while operating fast on occurrence of major fault currents, such as short-circuit currents, have a considerable time lag on occurrence of small protracted overloads, and whose time 25 lags are sufficiently long to allow application of the fuses in motor circuits where blowing of fuses must not occur as a result of harmless motor starting inrush currents.

These and other objects of the invention and advantages thereof will become more apparent from the ensuing detailed description of the invention and the features of novelty which characterize the invention will be pointed out with particularity in the claims annexed to this specification and forming a part thereof.

For a better understanding of the invention reference 35 may be had to the accompanying drawings illustrating the invention wherein—

FIG. 1 is a side elevation of a fuse embodying the present invention;

FIG. 2 is an end view of the structure shown in FIG. 1; 40 FIG. 3 is a section of the structure of FIGS. 1 and 2 taken along 3—3 of FIG. 1 and showing some of the parts in front elevation rather than in section;

FIG. 4 is an isometric view of the link structure of 45 the fuse shown in FIGS. 1-3;

FIGS. 5a to 5d are front views and cross-sections, respectively, of link sub-assemblies for structures of the kind shown in FIGS. 1-3;

FIG. 6 is a diagram showing the melting times for a 50 given constant current plotted against the angle of the bend in the link assemblies of FIGS. 5a and 5b;

FIG. 7 is a diagram showing the melting times for a given constant current plotted against the spacing between the two fuse links of the structure of FIGS. 1-3; and

55 FIGS. 8a, 8b, 9a, 9b, 10a and 10b are transverse sections across electric fuses embodying this invention and illustrate some geometrical relations which are characteristic of such fuses.

Referring now to the drawing, and more particularly to FIGS. 1-4 thereof, reference numeral 1 has been applied to indicate a tubular casing of insulating material. Casing 1 is made of a cellulosic insulating material such as fiber. Casing 1 may also be made of layers of paper which are wound spirally one upon the other until the desired wall thickness for the casing is obtained.

65 Terminal caps 2 close casing 1 on each end thereof. A washer 6 of a fibrous heat resistant material is interposed between each rim of casing 1 and each terminal cap 2. Caps 2 as well as washers 6 are each provided with a cut-out, or stamped out, opening for the passage of knife blade contacts 5. The latter extend from the outside of casing 1 through

caps 2 and washers 6, into the inside of casing 1. Leaf springs formed to the shape of pins 3 extend transversely across caps 2, casing 1 and knife blade contacts 5, thus supporting the latter and firmly securing caps 2 to casing 1. The central portion of each pin-shaped spring 3 upon which knife blade contacts 5 are mounted is compressed, and the axially outer ends of pin-shaped springs 3 are expanded by means of drive screws 4 driven into the axially outer ends of pin-shaped springs 3. This resilient construction is disclosed and claimed in United States Patent 2,939,935 to Frederick J. Kozacka, Fuse Structure, June 7, 1960, and in United States Patent 3,007,020 to Frederick J. Kozacka, Fuse Structures, Oct. 31, 1961. Reference may be had to these two patents for further details regarding the way in which knife blade contacts 5 are supported in position and caps 2 secured to housing 1. The axially inner ends of knife blade contacts 5 are conductively interconnected by a pair of ribbon fuse links 8, sandwiching the axially inner ends of knife blade contacts 5. Each fuse link 8 is provided with five transverse lines 8a of circular perforations and the center line of perforations of each fuse link is associated with a link-severing overlay 9 of a low fusing point metal, e.g. of tin. Fuse links 8 are preferably made of copper or another metal having a relatively high fusing point, e.g. silver. Overlays 9 are preferably arranged on fuse links 8 in the fashion disclosed and claimed in United States Patent 2,988,620 to Frederick J. Kozacka, Time-Lag Fuses, June 13, 1961. Each fuse link 8 is in the shape of a substantially channel-shaped element and the arrangement of both fuse links 8 in regard to casing 1 is eccentric. As best shown in FIG. 4 each fuse link comprises a center strip 8' and a pair of lateral extensions 8'' enclosing angles γ with the center strip 8'. A gap 10 is formed between the juxtaposed longitudinal edges of lateral extensions 8''. The width of that gap may vary, and the angle γ may vary, as will be explained below more in detail. The angle γ should preferably be in the order of 30 degrees. As best shown in FIG. 4 each center strip 8' of fuse links 8 is provided with an axial extension 8c in the form of a tab to be brazed, or soldered, or otherwise conductively connected to an axially inner end of one of the knife blade contacts 5. A crease or pleat 8b is formed between axial extensions 8c and center strips 8c to impart a sufficient degree of flexibility to the fuse link structures. Fuse links 8 are entirely submersed in a body of quartz sand 7 inside of casing 1.

It will be apparent from the foregoing that in fuses embodying this invention the fuse link structure including all the current carrying portions thereof is arranged relatively close to the axis of the tubular casing 1 and relatively remote from the inner surface of the latter. The fuse link structure includes substantially juxtaposed portions forming parallel current paths and being more narrowly spaced from each other than each from the interior surface of casing 1. Both ribbon fuse links 8 are bent to form a pair of eccentric, substantially congruent, substantially channel-shaped or tubular structures extending in a direction longitudinally of casing 1. The spacing between the axes of said pair of channel-shaped or tubular link structures is substantially less than the spacing between each of said axes and said casing. In FIG. 8a showing diagrammatically the structure of FIGS. 1-4 reference character m has been applied to indicate the spacing between the axes of channel-shaped or tubular fuse link structures 8 and reference character n has been applied to indicate the minimum spacing between each of said axes and the inner surface of casing 1, and it is apparent that

$m < n$

The cross-section of the fuse links does not necessarily have to be triangular as in FIGS. 1-7 and in FIG. 8a but may, for instance, take the shape illustrated in FIG. 8b wherein reference character 8a has been applied to indi-

cate a pair of substantially tubular fuse link structures having all the essential structural characteristics of the fuse link structures described in connection with FIGS. 1-4, except for the fact that the fuse link structures 8a have more or less the shape of an elongated oval rather than the triangular shape shown in FIGS. 1-4 and 8a.

In FIGS. 8a and 8b reference character F_1 has been applied to indicate the portion of the total cross-sectional area of casing 1 situated outside of fuse link structures 8 or 8a, respectively, and reference characters F_2 have been applied to indicate the portion of the total cross-sectional area of casing 1 situated inside of tubular structures 8, or 8a, respectively. It is apparent that the first mentioned portion of the cross-sectional area of casing 1 by far exceeds the last mentioned portion thereof, i.e. that

$F_1 > 2F_2$

It will be further apparent from FIGS. 1-4 and 8a that fuse links 8 are arranged in spaced relation each having a center portion 8' situated in one of a pair of substantially parallel planes. In FIGS. 8a and 8b reference character X has been applied to indicate the spacing between said pair of parallel planes.

FIGS. 9a and 9b are identical to FIGS. 8a and 8b and illustrate some additional important geometrical relations of the constituent parts of fuses embodying this invention. In FIGS. 9a and 9b reference character X has been applied to indicate the spacing between fuse links 8 and 8a, respectively. Reference character b has been applied to indicate the smallest spacing between fuse links 8 and 8a, respectively, from the interior of casing 1. It will be apparent that

$x < b$

i.e. fuse links 8 and 8a, respectively, are more narrowly spaced from each other than from the interior surface of casing 1. As a general rule

$b > > x$

i.e. the minimum spacing of the fuse links 8 from casing 1 should by far exceed the spacing between the fuse links.

In FIGS. 9a and 9b reference character r has been applied to indicate the maximum spacing of the lateral extensions 8'' and 8a'', respectively, of the fuse links from the center strips thereof marked 8' and 8a', respectively. The spacing r is much smaller than the minimum spacing b of each pair of lateral extensions 8'', 8a'' from the interior surface of casing 1, i.e.

$r < < b$

In FIGS. 10a and 10b showing the same structure as FIGS. 8a and 9a, and FIGS. 8b and 9b, respectively, reference character s has been applied to indicate the spacing between the longitudinal axes of fuse links 8 and 8a, respectively. In FIGS. 10a and 10b the minimum spacing between the longitudinal axes of fuse links 8 and 8a, respectively, and the inner surface of casing 1 has been designated by the reference character S . It will be apparent that

$s < < S$

i.e. the spacing between the axes of fuse links 8 and 8a, respectively, is substantially less than the minimum spacing between said axes and the inner surface of casing 1.

FIGS. 8a, 8b, 9a, 9b, 10a and 10b have been drawn to better show the aforementioned relations, but these figures do not indicate the most desirable proportions of a structure embodying the present invention. FIGS. 1-3, inclusive, are, however, scale drawings of a fuse embodying this invention, having a current rating of 400 amps and a voltage rating of 600 volts, and having been successfully subjected to a wide variety of low current interrupting tests and of high current interrupting tests.

As a result of the aforementioned geometrical relations the fuse links 8 and 8a, respectively, require a larger amount of metal than comparable prior art fuses, i.e.

prior art fuses having a comparable current-carrying-capacity and interrupting capacity at a predetermined voltage rating and tested in a predetermined circuit having predetermined characteristics, particularly as far as the rate of rise of the recovery voltage is concerned. Because fuses having the aforementioned relations between the constituent parts thereof require a relatively larger amount of link metal than comparable prior art fuses to achieve the same current-carrying-capacity, or the same current rating, or the same minimum fusing current, the ohmic resistance of their fuse links is relatively small. Hence their watt losses tend to be relatively small. The drastic limitation of watt losses coupled with a relatively large spacing between the fuse link structure and the inner surface of the casing makes it possible to use cellulosic casing materials in spite of the fact that the arc-quenching filler is quartz sand, or another arc-quenching filler material having a similarly high thermal conductivity and, therefore, resulting in a relatively small temperature gradient between the wall of the casing and the region inside the casing where the fuse links are arranged.

The following data give some indication of the reduction of watt losses resulting from the above fuse link geometry and casing geometry. A fuse structure as shown in FIGS. 1-3, inclusive, having a current rating of 400 amps and a voltage rating of 600 volts had a voltage drop of 80 millivolts when carrying its rated current. Comparable modern prior art fuses exhibited under the same conditions a voltage drop of 95 millivolts.

A reduction of watt losses is desirable irrespective of whether or not it is desired to make the casing of a cellulosic material. Therefore the above geometry of the fuse link and of the casing is not limited to casings of cellulosic material but is indicated wherever it is desired to have a cool running fuse in spite of the presence of an arc-quenching filler which is such a good thermal conductor as quartz sand and tends to minimize the radial voltage gradient within the tubular casing.

Since the above geometry of the fuse links and of the casing tends to increase the relative amount of link metal, or the ratio of the amount of link metal to the current-carrying-capacity of the fuse structure, it is conducive to relatively long delay times for fusion of the link-severing overlays 9, and concomitant initiation of the interrupting process on occurrence of relatively small overload currents. In other words, the above geometry of the fuse links and of the casing tends to result in time delay, or time lag, at relatively small overload currents and is, therefore, indicated wherever a time delay action is required, or desired. Since the time delay action is primarily a result of the geometry of the fuse link and of the casing, the application of this geometry is indicated wherever time delay is a desired operating characteristic, i.e. the application of this geometry may be desirable irrespective of the nature of the material of which the casing is made and irrespective of the thermal characteristics of the pulverulent arc-quenching filler interposed between the fuse link structure and the casing.

Referring now to FIGS. 5a-5d, each of these figures shows a pair of spaced blade contacts 5 conductively interconnected by a pair of identical perforated stampings of sheet copper forming fuse links 8. According to FIG. 5a the pair of stampings conductively interconnecting blade contacts 5, comprise a center strip 8' having two lateral extensions 8" forming therebetween a narrow gap 10. The lateral extensions 8" enclose angles of 26 degrees with center strip 8'. FIG. 5b differs from FIG. 5a in that in the former the angle enclosed between the center strips 8' and the lateral extensions 8" thereof is 45 degrees. As shown in FIG. 5c this angle is increased to 90 degrees. According to FIG. 5d the center strips 8' and the lateral extensions 8" of each fuse link 8 are arranged in the same plane or, in other words, the above angle has been increased from 90 degrees to 180 degrees.

FIG. 6 shows the times required to initiate interruption 75

in fuses embodying the structures of FIGS. 5a-5d when carrying the same current plotted against the angle enclosed between the center strips 8' and the lateral extensions 8". It is apparent that the fusing time increases rapidly as the aforementioned angle is increased and decreases rapidly as the aforementioned angle is decreased. Hence to achieve the same current-carrying-capacity, or the same minimum fusing current, with the structure of FIGS. 5a or 5b requires significantly thicker sheet metal than with the structure of FIG. 5d. Hence with the structures of FIGS. 5a and 5b watt losses are significantly smaller and time lags significantly longer than with the structure of FIG. 5d.

In FIG. 7 the times required to initiate fusion of the links in the structure of FIGS. 1-3 when carrying a predetermined constant current are plotted versus the spacing X between center strips 8'. It is apparent from FIG. 7 that fusing time increases rapidly as the aforementioned spacing X is increased, and decreases rapidly as the aforementioned spacing X is decreased. Hence to achieve the same current-carrying-capacity, or the same minimum fusing current, with a structure having a relatively small spacing X calls for significantly thicker sheet metal than with a structure having a relatively large spacing X. As a result watt losses are significantly smaller, and time lags significantly larger, as the spacing is reduced to the order of the thickness of the blade contacts, as shown in FIG. 1.

Although this invention has been described in considerable detail, it is to be understood that such description is illustrative rather than limiting, as the invention may be variously embodied, and is to be interpreted as claimed.

I claim as my invention:

1. An electric fuse comprising in combination:

- (a) a tubular casing of cellulosic insulating material;
- (b) a pulverulent silicious high heat conductivity arc-quenching filler within said casing;
- (c) a pair of metallic terminal elements closing the ends of said casing;
- (d) a pair of fuse-link-severing elements of a relatively low fusing point metal; and
- (e) a pair of ribbon fuse links of a relatively high fusing point metal arranged inside said casing, submerged in said filler, conductively interconnecting said pair of terminal elements and each supporting one of said pair of fuse-link-severing elements, each of said pair of link-severing elements extending transversely across one of said pair of fuse links, said pair of fuse links being bent to form a pair of eccentric substantially congruent substantially tubular structures extending in a direction substantially longitudinally of said casing, and the spacing between the axes of said pair of tubular structures being substantially less than the spacing between each of said axes and the inner surface of said casing.

2. An electric fuse comprising in combination:

- (a) a tubular casing of insulating material;
- (b) a pulverulent arc-quenching filler within said casing;
- (c) a pair of metallic terminal elements closing the ends of said casing;
- (d) a pair of fuse-link-severing elements of a relatively low fusing point metal; and
- (e) a pair of ribbon fuse links of a relatively high fusing point metal arranged inside said casing, submerged in said filler, conductively interconnecting said pair of terminal elements, and each supporting one of said pair of fuse-link-severing elements forming an overlay on one of said pair of links extending continuously from one lateral edge to the other lateral edge thereof, said pair of fuse links being bent to form a pair of eccentric substantially congruent narrowly spaced substantially tubular structures extending in a direction substantially longitudinally of said casing, the portion of the cross-sectional area of said

casing situated outside of said pair of tubular structures by far exceeding the portion of the cross-sectional area of said casing situated inside of said pair of tubular structures.

3. An electric fuse comprising in combination:

- (a) a tubular casing of hard fiber;
- (b) a high heat conductivity quartz sand filler within said casing;
- (c) a pair of metallic terminal elements closing the ends of said casing;
- (d) a pair of ribbon fuse links of copper inside said casing submersed in said filler conductively interconnecting said pair of terminal elements, said pair of fuse links including juxtaposed web portions forming parallel current paths being more narrowly spaced from each other than the spacing of any point thereof from the interior surface of said casing and each of said pair of fuse links including a pair of flange portions enclosing angles of less than 45 degrees with the web portion thereof; and
- (e) a pair of link-severing overlays of a metal having a substantially lower fusing point than copper each affixed to one of said pair of fuse links, said pair of overlays extending transversely across said web portions of said pair of fuse links and transversely across said pair of flange portions of each of said pair of fuse links, and said pair of overlays reducing the minimum fusing current of said pair of fuse links sufficiently to preclude substantial thermal damage to the hard fiber of said casing on occurrence of protracted currents in the order of said reduced minimum fusing current.

4. An electric fuse comprising in combination:

- (a) a tubular casing of cellulosic insulating material;
- (b) a pulverulent high heat conductivity quartz filler within said casing;
- (c) a pair of metallic terminal elements closing the ends of said casing;
- (d) a pair of fuse-link-severing elements of a relatively low fusing point metal;
- (e) a pair of blade contacts projecting from the outside of said casing through said pair of terminal elements into the inside of said casing;
- (f) a pair of separate ribbon fuse links of a relatively high fusing point metal inside said casing submersed in said filler conductively interconnecting said pair of blade contacts and each supporting one of said pair of fuse-link-severing elements, each of said pair of fuse-link-severing elements extending transversely across one of said pair of fuse links, said pair of fuse links having portions arranged in a pair of substantially parallel planes having a narrower spacing from each other than the average spacing of each of said pair of fuse links from said casing, each of said pair of fuse links having a pair of integral lateral extensions arranged outside of said pair of parallel planes, and each of said pair of lateral extensions being substantially juxtaposed to one of said portions of said pair of fuse links.

5. An electric fuse comprising in combination:

- (a) a tubular casing of cellulosic insulating material;
- (b) a pulverulent silicious high heat conductivity arc-quenching filler within said casing;
- (c) a pair of metallic terminal elements closing the ends of said casing;
- (d) a pair of fuse-link-severing elements of a relatively low fusing point metal; and
- (e) a pair of separate ribbon fuse links of a relatively high fusing point metal arranged inside of said casing, submersed in said filler, conductively interconnecting said pair of terminal elements and each supporting one of said pair of link-severing elements, each of said pair of fuse-link-severing elements extending transversely across one of said pair of fuse links, said pair of fuse links including

portions arranged in spaced relation in a pair of substantially parallel planes having a smaller spacing from each other than the minimum spacing of each of said pair of fuse links from said casing, each of said pair of fuse links having a pair of lateral extensions integral therewith enclosing acute angles with said portions of said pair of fuse links, and each of said portions of said pair of fuse links having a smaller maximum spacing from said pair of lateral extensions thereof than the minimum spacing of each of said pair of lateral extensions from the interior surface of said casing.

6. An electric fuse comprising in combination:

- (a) a tubular casing of insulating material;
- (b) a pulverulent arc-quenching filler within said casing;
- (c) a pair of metallic terminal elements closing the ends of said casing;
- (d) a pair of fuse-link-severing elements of a relatively low fusing point metal; and
- (e) a pair of separate ribbon fuse links of a relatively high fusing point metal arranged inside of said casing, submersed in said filler, conductively interconnecting said pair of terminal elements, and each supporting one of said pair of fuse-link-severing elements, each of said pair of fuse-link-severing elements extending transversely across one of said pair of fuse links, said pair of fuse links having portions arranged in spaced relation in a pair of substantially parallel planes having a smaller spacing from each other than the minimum spacing of each of said pair of fuse links from said casing, each of said pair of fuse links having a pair of lateral extensions integral therewith enclosing acute angles with said portions of said pair of fuse links, and each of said portions of said pair of fuse links having a smaller maximum spacing from said portions of said pair of fuse links than the minimum spacing of each of said portions of said pair of fuse links from the interior surface of said casing.

7. An electric fuse comprising in combination:

- (a) a tubular casing of insulating material having a predetermined cross-sectional area;
- (b) a pulverulent arc-quenching filler within said casing;
- (c) a pair of terminal elements closing the ends of said casing;
- (d) a pair of substantially tubular fuse links of sheet metal arranged in spaced eccentric relation inside said casing, submersed in said filler and conductively interconnecting said pair of terminal elements, the total cross-sectional area encompassed by said pair of fuse links being substantially less than said predetermined cross-sectional area, and the spacing of the longitudinal axes of said pair of fuse links from each other being substantially less than the spacing of said longitudinal axes from said casing; and
- (e) a pair of substantially annular link-severing overlays of a metal having a substantially lower fusing point than said sheet metal each on one of said pair of fuse links.

8. An electric fuse comprising in combination:

- (a) a tubular casing of insulating material having a predetermined cross-sectional area;
- (b) a pulverulent arc-quenching filler within said casing;
- (c) a pair of terminal elements closing the ends of said casing;
- (d) a pair of knife blade contacts each having a predetermined thickness each projecting from one of said pair of terminal elements in a direction longitudinally of said casing;
- (e) a pair of substantially tubular fuse links of sheet metal substantially triangular in cross-section ar-

ranged in spaced relation inside of said casing and submerged in said filler, the total cross-sectional area encompassed by said pair of fuse links being substantially less than said predetermined cross-sectional area, said pair of fuse links having a pair of juxtaposed sides having a spacing in the order of said predetermined thickness of said pair of blade contacts, each of said pair of opposite sides of said pair of fuse links being provided at the end thereof with a pair of connector tabs each forming a V-shaped 10 crease and each being conductively connected to one of said pair of blade contacts; and

(f) a pair of substantially triangular link-severing overlays of a metal having a substantially lower fusing point than said sheet metal each on one of said pair 15 of fuse links.

9. An electric fuse comprising in combination:

- (a) a tubular casing of insulating material;
- (b) a pulverulent arc-quenching filler within said casing;
- (c) a pair of terminal caps closing the ends of said casing;
- (d) a pair of blade contacts having a predetermined thickness each projecting from the outside of said casing across one of said pair of terminal caps into the inside of said casing;
- (e) a pair of link-severing overlays of a relatively low-fusing point metal; and

5

20

25

(f) a pair of ribbon fuse links of a relatively high fusing point metal conductively interconnecting said pair of blade contacts and each supporting one of said pair of link-severing overlays, each of said pair of fuse-link-severing overlays extending transversely across one of said pair of fuse links, said pair of fuse links including a pair of center strips having a spacing substantially equal to said predetermined thickness of said pair of blade contacts and each of said pair of fuse links including a pair of lateral extensions integral with one of said pair of center strips and enclosing an angle of less than 45 degrees with said one of said pair of center strips.
